UNITED STATES PATENT OFFICE

2,395,521

YARN WINDING APPARATUS

Pacific J. Thomas, Wyoming, Pa., assignor to
 U. S. Textile Machine Company, Scranton, Pa.,
 a corporation of Pennsylvania

Application January 29, 1944, Serial No. 520,337

6 Claims. (Cl. 242—37)

This invention relates to textile machines of the yarn winding and twisting type adapted to provide so-called "headless" yarn packages having a tapered or inclined end construction.

Textile machines of the referred to type wind the yarn on tubular spools, or cylinders, while simultaneously imparting to the yarn a predetermined twist. When such machines apply the yarn to the cylinders in progressively shortened yarn layers so as to effect inwardly inclined, or uniformly tapered yarn package ends, the yarn, during winding, has a tendency to more or less frequently drop off at said inclined ends. The dropped portion of the yarn is referred to in the trade as a "cross-over," and is detrimental for various reasons. For example, the accompanying yarn slackening and jerking action usually causes rupture of the yarn. Rectification of this difficulty involves machine production losses, yarn wastage and labor costs. The responsibility for such losses and difficulties is mainly attributable to the yarn feeding means of such machines and the inability of such means to effectively and efficiently perform its intended function under various operating conditions and speeds.

One object of my invention is to provide a novel textile machine of the referred to type which eliminates the mentioned and other losses and difficulties.

Another object is to provide such a machine having novel yarn feeding means.

Another object is to provide such a machine comprising a reciprocally operated yarn feeding element, the operating position of which is automatically adjusted in correspondence with the change in location of the yarn receiving surface of the device on which the yarn is wound, so that said element and surface will remain in determinedly fixed positional relationship throughout the entire yarn winding procedure.

It is also an object to provide such a machine having novel means for progressively varying the stroke of said yarn feeding element.

An additional object is to provide such a machine in which the stroke of said element is determined by novel means the movement of which is governed by the total thickness of the yarn layers applied to the yarn receiving device.

A further object is to provide such a machine comprising a rotary yarn receiving device and a reciprocally operated variable stroke yarn feeding element which is automatically maintained in contacting relationship with the yarn receiving surface of the device during the entire yarn wind-

ing cycle, including the inactive period or periods when the said device is temporarily disconnected from its driving means as a result of yarn breakage.

5 Another object is to provide such a machine in which a movable mounting for a rotary yarn receiving device is uniquely associated with tilttable track means to control the stroke of the yarn feeding element.

10 Another object is to provide such a machine with novel means for effecting the production of so-called "headless" yarn packages having tapered ends, which means has structural and functional features of advantage over similar means of the prior art.

15 With these and other objects in view, which will become more apparent from the following detailed description of certain practical and illustrative embodiments of my novel improvements, shown in the accompanying drawings, the invention comprises the novel elements, features of construction and arrangement of parts in cooperative relationship, as hereinafter more particularly pointed out in the claims.

20 Referring to the drawings:

Figure 1 is a partial front elevational view of certain well known parts of a standard yarn winding and twisting machine, having my invention applied thereto.

25 Fig. 2 is a fragmentary front elevational detail view of certain elements which are partly obscured in Fig. 1.

Fig. 3 is an enlarged elevational sectional view taken substantially as indicated by the arrows 3—3 on Fig. 2.

30 Fig. 4 is a top plan view of Fig. 1.

Fig. 5 is an enlarged horizontal sectional view, taken substantially as indicated by the arrows 5—5 on Fig. 2.

35 Fig. 6 is an elevational sectional view taken substantially as indicated by the arrows 6—6 on Fig. 1, with certain parts added.

Fig. 7 is an enlarged sectional detail view, taken 40 substantially as indicated by the arrows 7—7 on Fig. 6.

Fig. 8 is an enlarged sectional detail view, taken substantially as indicated by the arrows 8—8 on Fig. 6.

45 Fig. 9 is an enlarged sectional detail view, taken substantially as indicated by the arrows 9—9 on Fig. 1.

50 Fig. 10 is a horizontal sectional view, taken substantially as indicated by the arrows 10—10 on Fig. 6.

Fig. 11 is a view similar to Fig. 6, but with certain parts in another position.

Fig. 12 is a sectional detail view, taken substantially as indicated by the arrows 12-12 on Fig. 5.

Fig. 13 is a front elevational view of certain parts shown in the upper portion of Fig. 11, and

Fig. 14 is an enlarged fragmentary sectional view, taken substantially as indicated by the arrows 14-14 on Fig. 13.

In the drawings only those parts of a standard yarn winding and twisting machine of the "up-twister" type are shown as are necessary to a disclosure and understanding of my invention. For further information concerning the construction and operation of such machines, reference may be had to the various pertinent catalogs and other literature published for distribution by the U. S. Textile Machine Co. of Scranton, Pennsylvania, and other manufacturers of such machines. For additional information concerning certain prior art elements and mechanisms only partly illustrated in the drawings hereof, reference may also be had to the following U. S. patents:

Number	Date	Inventor
2,258,914	Oct. 14, 1941	P. J. Thomas.
2,258,899	Oct. 14, 1941	Royal Little et al.
2,258,900	Oct. 14, 1941	Royal Little et al.

The usual and well-known parts of each individual yarn winding and twisting machine unit include a yarn supply spool 15 mounted on and rotated with a twister spindle 16, and a take-up roll or bobbin 17 which is operated by direct frictional engagement with a driving drum 18. The twister spindle 16 and driving drum 18 are continuously rotated at predetermined twisting and winding speeds. The yarn "Y" is drawn upwardly from the spool 15, through yarn guides 19 and 20 over a fixed guide member 21 through a yarn guide or feeding element 22, to the surface of the take-up roll 17. The yarn guide member 21 is provided at its ends with enlargements or collars 21^a having hooks 21^b. The yarn feeding element 22 is reciprocated by a traversing rod 23 extending lengthwise of the machine and guided for movement in a multiplicity of roller bearings 24, as determined by the usual traversing rod operating mechanism, not shown. Determined reciprocation of the guide element 22 effects the laying of the yarn Y on take-up roll 17 in desired order.

The take-up roll 17 is provided, as usual, with trunnions 17^a which are adapted to be seated for rotary movement in slotted bearing elements 25^a clamped in position by bolts 25^b between the split sections of the bifurcated upper ends 25^a of a swinging support or frame 25. Secured in the lower side sections of the frame 25 are two pivot studs 26 which extend into fixed bearings 27 of a bracket 28 secured to a stationary machine frame member 29. A spiral-compression spring 30 (Fig. 6) is interposed between a support or extension 31 on the bearing bracket 28 and a lug 32 projecting rearwardly from the frame 25, and tends to urge the supporting frame 25 and roll 17 to move to the left in Fig. 6. However, this tendency of movement of the frame 25 is normally counteracted and overcome by the force of a relatively stronger spiral spring 33, one end of which is anchored to an extension 34^a forming the rear end of a bar 34, and the other end of which spring is connected to a stud 35 fixed to the frame 25, which stud extends through an elongat-

ed slot 34^b in the bar 34. The spring 33 is tensionally arranged between the stud 35 and extension 34^a in such manner as to normally maintain the take-up roll 17 in yielding operating contact with the driving drum 18.

The arrangement of the bar 34, yarn guides 19 and 20, and certain associated parts partly shown in Figs. 6 and 11, is such as to form a "stop motion mechanism for twisting and winding machines" of the type constituting the subject matter of my above noted Patent No. 2,258,914, to which reference may be had for a complete disclosure of its construction and operation. This patented stop motion mechanism operates when the yarn Y breaks or runs out, and the yarn guide 20 functions as a detector element in this combination. When the yarn Y breaks or runs out, the guide 20 and certain associated parts (not shown) effect release of the bar 34 for movement to the left in Fig. 6, so that the spring 33 no longer exerts a rearward pull on the frame 25. The frame 25 and the roll 17 are then free to move forward (to the left in Fig. 6) under the influence of spring 30, thus breaking the driving contact between the roll 17 and the drum 18. Rotation of the roll 17 thereupon promptly ceases.

Cooperatively combined with the previously described elements and mechanisms are novel means for controlling the stroke of the yarn feed element 22 to effect winding of the yarn Y on the take-up roll or cylinder 17 in such manner that the yarn and cylinder will form a so-called "headless" yarn package having tapered or inclined ends. Such means generally comprise a track member 36, a carriage 37, a connecting rod 38 the upper end of which is provided with a ball 39 arranged to form a universal joint with an adjustable socket device 40 secured to track member 36, and an adjustable socket device 41 on the lower end of rod 38 which forms a universal joint with a ball 42 on the end of a stud 43 adjustably secured to the lower portion of the frame 25.

The track member 36 is pivotally secured by a shouldered rivet 44 to a bracket 45 fixed to a longitudinally extending stationary machine beam or rod 46. As clearly shown in Fig. 12, a shouldered portion of the socket device 40 extends through a vertical slot 45^a in the bracket 45 to permit free movement of the socket device 40 relative to the bracket 45. A flange 47 formed on the upper end of the track member 36 serves as a runway for a roller 48 secured for free rotation to the carriage 37, which latter is pivotally connected by a shouldered stud rivet 49 with a bracket 50 fixed to the traversing bar 23.

In order that the roller 48 may be constantly maintained in cooperative relation with the flange 47 of the track member 36, a spring wire 51 is coiled about the shouldered stud rivet 49, one end of which wire rests on an extension 52 of the bracket 50, and the other end of which wire rests on the upper edge of the carriage 37. By this arrangement the spring wire 51 exerts a downward pressure on the portion of the carriage 37 to the right (Fig. 5) of its pivotal connection with the bracket 50, thereby maintaining the roller 48 in engagement with the flange 47.

The yarn guide or feed element 22 is secured to the upper end of a plate 53 which is pivotally connected with the carriage 37 by means of a pin 54 the ends of which are mounted in bearing flanges 55 of the carriage. This arrangement permits the element 22 to move laterally with

respect to the take-up roll 17. The forward, or feeding end of the element 22 is arranged to rest against the take-up roll 17, or the yarn receiving surface thereof established by the successive yarn layers as the winding of the yarn proceeds. Since the element 22 will at all times be positioned to the right (Figs. 6 and 11) of the pivot pin 54, during a particular yarn winding operation or cycle, contact of the element 22 with the yarn receiving surface of the take-up roll 17 will be automatically maintained by the gravitational force acting on the element 22. Of course, if desired, a spring may be connected to the plate 53 and carriage 37 in such manner that the spring will accomplish the same purpose as the referred to gravitational force, or the spring can be provided to supplement the latter.

Since standard yarn winding and twisting machines of the type herein referred to usually comprise a long frame structure along both sides of which are mounted duplicate rows of similar machine units, it will be understood that the machine or apparatus of my invention is provided with the usual complement of such units each embodying the elements and mechanisms previously described.

The operation of each such individual unit involves substantially the following:

When starting a yarn package, the end of the yarn is wrapped around a fresh or empty take-up roll 17, in usual manner, and the latter is then mounted in its bearing elements 25 at the upper end of the swinging frame 28. The bar 34 is then moved rearward by manual pressure on the knob 60 until the spring 33 is under the tension required to place the take-up roll 17 in driving contact with the drum 18, and the previously referred to "stop motion mechanism" is set for operation in accordance with the disclosure of my said Patent No. 2,258,914. The various elements and mechanisms will then be cooperatively related substantially as shown in Fig. 6.

Rotation of the yarn supply spool 15, and driving drum 18, as usual, effects procedure of the yarn winding operation. As the successive yarn layers on the take-up roll 17 move the upper end of the swinging frame 28 laterally away from the drum 18, the connecting rod 38 will be operated in direct correspondence with this movement, with the result that the pivotally mounted track member 36 will be tilted from its initial horizontal position by an amount varying in direct correspondence with the total thickness of the yarn layers on the take-up roll 17. Reciprocation of the carriage 37 by the traversing rod 23 effects movement of the roller 48 along the track or runway 47, back and forth, thereby correspondingly moving the yarn feed element 22 at the upper end of the plate 53 which is pivotally connected with the carriage 37. As the angle of tilt of the track 47 increases, the stroke of the yarn feed element 22 decreases. This will become more apparent by reference to Fig. 13, which depicts the carriage 37 and the yarn feed element 22 at the extreme ends of their stroke to the right and left, at the time that the take-up roll 17 is substantially supplied with its intended quantity of yarn. At this time, the swinging frame 28, connecting rod 38 and the associated parts, will occupy a position substantially as depicted by Fig. 11.

Should the yarn break, or run out, during the winding operation, the detector element or yarn guide 26 will release the bar 34 for movement to the left (Figs. 6 and 11), as previously indicated,

thereby effecting disengagement of the driving connection between the take-up roll 17 and drum 18, so that rotation of the roll 17 ceases.

It will be noted that during the winding operation, the yarn feed element 22 is continuously in direct contact with the surface to which the yarn is applied, and that the yarn is consequently guided to its exact point of application at all times. This feature, in conjunction with the means for progressively varying the stroke of the yarn feed element in direct correspondence with the total thickness, or diameter, of the yarn layers applied to the take-up roll 17, results in the same precise yarn applying action under varying conditions, such as a change in speed of operation of the machine, or a change in the denier of the yarn to be wound.

Of course, the improvements specifically shown and described can be changed and modified in various ways without departing from the invention herein disclosed and more particularly defined by the appended claims.

I claim:

1. A textile apparatus of the character described comprising a movable mounting, a yarn receiving device rotatably supported on said mounting, a yarn feeding element arranged to contactingly move along the yarn receiving surface of said device, means maintaining the element in contact with said surface during the winding of the yarn thereon, tiltable track means cooperatively associated with said element and arranged to determine the extent of its reciprocal movement, and means connecting said movable mounting and track means.

2. A textile apparatus of the character described comprising a movable mounting, a yarn receiving device rotatably supported on said mounting, a yarn feeding element arranged to contactingly move along the yarn receiving surface of said device, mounting means arranged to support the element in such manner that it will remain in leaning contact with said surface during the winding of the yarn thereon, longitudinally tiltable track means, carriage means associated with said element and arranged to travel on said track means, and means arranged to determine the angle of tilt of the track means.

3. A textile apparatus of the character described comprising a movable mounting, a yarn receiving device rotatably supported on said mounting, a yarn feeding element arranged to contactingly move along the yarn receiving surface of said device, means maintaining the element in contact with said surface during the winding of the yarn thereon, longitudinally tiltable track means, carriage means arranged to travel on said track means, means pivotally connecting said element with the carriage means and means connecting said movable mounting and track means.

4. A textile apparatus of the character described comprising a movable mounting, a yarn receiving device rotatably supported on said mounting, means arranged to rotate the yarn receiving device, a yarn feeding element arranged to contactingly move along the yarn receiving surface of said device, means maintaining the element in contact with said surface during the winding of the yarn thereon, longitudinally tiltable track means, carriage means provided with an anti-friction device arranged to travel on said track means, means pivotally connecting said element with the carriage means, and means

arranged to directly transmit the movement of said movable mounting to the track means.

5. A textile apparatus of the character described comprising a movable mounting, a yarn receiving device rotatably supported on said mounting, means arranged to rotate the yarn receiving device, a yarn feeding element arranged to contactingly move along the yarn receiving surface of said device, means maintaining the element in contact with said surface during the winding of the yarn thereon, longitudinally tiltable track means, carriage means arranged to travel on said track means, means pivotally connecting said element with the carriage means, and motion translating means connecting said movable mounting and track means including one or more universal joints.

6. A textile apparatus of the character de-

scribed comprising a movable mounting, a yarn receiving device rotatably supported on said mounting, means arranged to rotate the yarn receiving device, a yarn feeding element arranged to contactingly move along the yarn receiving surface of said device, means maintaining the element in contact with said surface during the winding of the yarn thereon, means operative upon breakage of the yarn to effect disconnection of the yarn receiving device from the means arranged to rotate the latter, longitudinally tiltable track means, carriage means arranged to travel on said track means, means pivotally connecting said element with the carriage means, and means connecting said movable mounting and track means.

PACIFIC J. THOMAS.
